(57) **CLAIM**

The ornamental design for a head portion of a toothbrush, as
shown and described.

DESCRIPTION

FIG. 1 is a perspective view of a portion of a toothbrush head
according to the present invention;

FIG. 2 is an elevational view of the head portion according
to the present invention;

FIG. 3 is an elevational view opposite from that shown in
FIG. 2, of the head portion according to the present invention;

FIG. 4 is a planar view of the head portion according to the
present invention;

FIG. 5 is a planar view opposite from that shown in FIG. 4,
of the head portion according to the present invention; and,
FIG. 6 is an end view of the head portion according to the
present invention.

The neck portion is shown broken away to indicate an
unspecified length.
